Application September 16, 1942, Serial No. 458,490
 In Sweden January 7, 1942

4 Claims. (Cl. 102—7.4)

1

The present invention relates generally to projectiles and particularly to devices for igniting bursting charges of projectiles, for example rifle grenades, grenades for trench mortars and guns, aerial bombs to be dropped from airplanes and the like.

The object of the invention is to cause the bursting of the projectile, grenade or bomb immediately above or close to the target, before the projectile has had time to penetrate into the soil or below the surface of the earth.

A projectile according to the present invention is of the kind having no retarding means, but being provided with steering fins for guiding the projectile in its trajectory.

A projectile according to the invention comprises in combination a casing having straight external steering fins for guiding the projectile in its trajectory, a bursting charge with its detonator, fuse and fuse cap within said casing, a striker head with firing pin at an operable distance from said fuse cap, a stiff precursor of desired length and ejectable from the casing, means to eject the said precursor, said precursor being adapted upon ejection to be so rigidly coupled to the said striker head so that the striker head and its firing pin are operated upon impact of the front part of said precursor against the target, and means wholly within the projectile to cause delayed release of the said ejecting means for the ejection of said precursor at a chosen time after the projectile has departed from its starting place and after the projectile has been stabilized with its striker head forward in its predetermined trajectory.

When the ejected front part of the precursor strikes the earth or the target, the striker head with firing pin or the firing device is caused to detonate the charge.

The release of the precursor can take place in several ways of which only a few will be here described. The invention is, however, not limited to the embodiments here shown, but refers generally to all grenades, projectiles and bombs that shall be caused to explode immediately before the projectile proper strikes the target.

By means of the invention a substantially increased action on living targets, vehicles, armoured cars, tanks and the like can be obtained as well as on buildings and the like that shall be wrecked or be made unsuitable for further use.

The principle of the invention will be further understood from the attached drawing of which—

Fig. 1 is a vertical section of a service fuse of

2

a projectile according to one embodiment of the invention.

Fig. 2 is a horizontal view of a section of the fuse showing an embodiment of the invention comprising safety devices and devices for release of a precursor ejectable from the fuse.

Fig. 3 is a vertical section at about 90° to the section of the fuse shown in Fig. 1.

Fig. 4 is a vertical section of another embodiment of the lower part of the precursor or tube shown in Fig. 1 with modified means of release of the precursor.

Fig. 5 is a horizontal section of the device shown in Fig. 4.

Fig. 6 represents a view partly in section of a grenade or aerial bomb according to the invention and provided with casing, steering fins and bursting charge.

In Figs. 1-3 showing a fuse for a grenade for a trench mortar, the pin 1 serves as safety device during transportation, by means of which pin the piston 2 is kept in locked position. The piston 2 is kept in normal position by the safety spring 3 which serves as safety device at the loading operation.

Due to the jerk at the moment of firing the safety spring 3 is knocked out of shape allowing the piston 2 to be thrown backwards so that the rotor 4 with its fuse cap 5 and fuse 151 are freed. The rotor can be turned by means of the spiral spring 7 attached at one end to the central tube 6 and at the other end being fastened to a pin 8 attached to the rotor. When said pin 8 upon rotation of the rotor meets the firing pin 9, the upper fuse cap 5 and fuse 151 will be located exactly under the firing pin and also exactly over a fuse 11 located in the fuse body 10. The central tube 6 is attached to the fuse body 10 by means of the fastening bolt 12. The firing pin 9 is attached to the striker head 13 kept in its normal position by the spring 14 which serves as safety device in the trajectory of the grenade.

The safety spring 14 is securely held between the upper fixed part of the central tube 6 and the striker head.

The central tube 6 is at its upper part provided with two slits for guiding the striker head by means of the small pistons 17 which by means of spiral springs 18 are pressing against the movable precursor 19. By means of the small pistons 17 the striker head is prevented from turning with respect to the central tube 6, which is provided with a swelling 20 resting on the fuse body 10 to prevent the central tube from moving

axially due to acceleration at the ejection of the projectile from the mortar barrel.

On the upper part of this swelling 20 there is a washer 15 which by means of a lip protruding into one of the slits 16 is prevented from turning with respect to the central tube. On the washer 15 is fastened the pin 21 about which the lever 22 is turnable. The other end of lever 22 is normally resting against stop pin 8 on the rotor 4. The lever is provided with a conical tip 23 entering into a corresponding hole of the precursor 19 by means of which said precursor is locked in its normal position shown in the drawing. Within the precursor 19 there is located a spiral spring 24 which has a tendency of ejecting the precursor, but is prevented from said ejecting action by the stud or tip 23 of the lever 22. The lower part of the precursor 19 is provided with a swelling 25 partly to steer the precursor and partly to serve as a stop against the upper part of the striker head, when the precursor is ejected.

The device shown in Figs. 1-3 operates in the following way. The safety pin 1 is pulled out before introducing the projectile in the barrel of the mortar. By means of the pin 1 the safety piston 3 and the precursor 19 are normally locked. At the firing the safety spring 3 is knocked out of shape allowing the piston 2 to be thrown backwards. Hereby the rotor 4 becomes free, but safety against operation of the rotor within the barrel is obtained thereby that during the greater part of the passing of the projectile through the barrel the rotor is so heavily pressed against the fuse body that the spring 7 cannot move the rotor.

When the acceleration of the projectile after leaving the gun barrel is sufficiently lessened and retardation on account of the air resistance takes place, the rotor begins to turn until the fuse cap 5 is located in front of the firing pin 9. When the rotor starts to turn, the pin 8 leaves its normal position, and the lever 22 becomes free to turn about its pin 21.

The stud or tip 23 on the lever 22 has been given such a conical angle that when the acceleration and the air resistance on the front part of the precursor have been sufficiently lessened the force of the spring 24 is sufficient to push the lever 21 and its conical stud 23 to the side, whereafter the precursor is ejected until its lower swelled part is stopped by the inner upper wall of the striking head and locked due to the conical shape of the upper part of the lower swelled part of the precursor. Hereby the lower part of the precursor has passed the small pistons 17 which now protrude behind the bottom of the precursor and lock it in its forward operating position to the striker head.

When the projectile is arriving at the target, it is the front part of the precursor that hits the earth or the target. As the precursor now is locked to the striker head, said head together with the firing pin is pushed towards the fuse cap 5 and fuse 151, which fires the fuse 11. The latter fires the detonator 26, which is screwed into the top nut 27 and carries the detonation further to the bursting charge inside the casing.

In Fig. 4 and Fig. 5 another embodiment of the locking device of the precursor is shown. Instead of the lever 22 and the stud 23 shown in Fig. 2, two studs 28 and 29 are fastened to the central tube 6. The precursor is at its rear end provided with an opening 39 of suitable form. The precursor is prevented from being ejected by the 75

upper stud 28 the protruding part of which normally rests in an upper notch of the opening 30.

Upon firing the precursor is thrown backwards on account of the acceleration of the projectile and due to the inertia of the precursor. The precursor is thereby forced to turn, because the lower stud 29 engages the inclined wall 31 of the precursor so that the precursor is freed from engagement with the upper stud.

When the acceleration and the air resistance are sufficiently lessened, the spring 24 can eject the precursor, as above described with reference to Figs. 1-3, and the projectile will be fully armed before hitting the target.

The embodiments shown in Figures 1-5 refer to projectiles for trench mortars, whereby the projectile is provided with fins so arranged that the projectile follows the trajectory without rotating. It is, however, understood that the invention can also be used on projectiles provided with fins and fired from guns with smooth bores. It can also be used in aerial drop bombs without rotation. The action of release of the precursor must in each case be determined under consideration of the initial acceleration, length of trajectory, retardation, etc., of the projectile, said release to take place only after the projectile has been stabilized with its striker head forward in its definite trajectory; pyrotechnical devices can be used both for delaying the ejection of the precursor and for its ejection.

In Fig. 6 element 61 is the casing of a grenade or aerial bomb. Elements 62 are steering fins. Element 63 is a bursting charge, in the center of which a fixed pipe 6 is located, and inside which pipe the precursor 19 is arranged to be projected by means of a spring 24 as shown in Fig. 1.

Instead of using spring pressure to eject the precursor, any other force can be used either combined with the acceleration at the firing or without same. The rear end of the precursor 19 can thus be shaped as a piston within the central tube 6, and a small powder charge can be placed at the bottom of tube 6.

According to another embodiment, the device can be provided with a time fuse adapted to start operating at the firing of the projectile. The time fuse is previously adjusted to operate a pyrotechnical device which fires, for example, a powder charge, after the projectile has passed the greater part of the trajectory, for example, 50 to 100 meters from the target, whereby the rear part of the precursor in the shape of a piston is pressed outwards, until the small pistons 17 lock the precursor in its operating position before striking the target.

The central tube 6 and the precursor 19 can eventually pass through the whole body of the projectile and be combined with a time fuse, for example, in the form of a light-tracer charge, the size of which is so calculated that after a certain number of seconds the fire cap and a small powder charge is fired, whereby the piston pushes the precursor to its operating position.

In order to obtain the explosion at a suitable distance before or above the target, the precursor can be made considerably longer than shown on the drawing by making them composed of several parts in telescopic form, which parts upon delayed firing of a powder charge or corresponding means will be pushed out and interlocked to form a single long precursor.

In order not to impair the stability of the ordinary trajectory of the projectile, the front part of the precursor can be filled with a heavy weight,

for example lead, which will act as stabilizing agent on both the precursor and on the projectile as a whole after the precursor has been ejected. The heavy front part of the precursor will also lessen its tendency to vibrate due to side wind pressures.

According to the present invention the construction of a fuse according to Figs. 1-3 with a precursor 19 can be used in combination with aerial drop bombs with the following modification. As no acceleration step for releasing of the rotor 4 takes place when a bomb is released from a bombing machine, the piston 2 and safety spring 3 are suppressed. Instead of spring 7 for turning the rotor 4, the rotor can be provided with a cogwheel fixed to the outer side of the rotor. A shaft with a small cogwheel to engage the larger cogwheel on the rotor is attached to a washer fixed to the central tube 6. The shaft of the small cogwheel is coupled to a spiral spring or clockwork, which has a tendency to drive the cogwheels and the rotor. The safety pin 1 holds the precursor 19 and the rotor 4 in normal position during transports and handling.

The device operates in the following way. Upon release of the bomb from the bombing machine the pin 1 is automatically pulled out, thereby leaving the precursor and the rotor free to move. The clockwork acting on the rotor through the cogwheels begins to move the rotor until the fuse cap 5 is in front of the fire pin 9. Simultaneously the precursor 19 has been released and ejected and coupled to the striker head 13 as previously described. By choosing the proper size of the cogwheels a suitable time can be obtained before the fuse is fully armed after the bomb has fallen a sufficient safe distance from the bombing machine and has been stabilized in its trajectory.

What we claim is:

1. A projectile comprising in combination, a 40 casing having straight external steering fins for guiding the projectile in its trajectory, a bursting charge, a detonator for said charge, a fuse and a fuse cap all within said casing, a striker head including a firing pin at an operable distance from said fuse cap, a stiff precursor of 45 desired length and projectable from the casing, means to project the said precursor, means to couple said precursor, upon its projection, so rigidly to said striker head that the latter and its 50 firing pin are operated upon impact of the front

part of said precursor against the target, and means wholly within the projectile to delay the operation of said projecting means for a predetermined length of time after the projectile has departed from its starting place so as to permit stabilization of the projectile with its striker head directed forwardly in its predetermined trajectory.

2. A projectile as claimed in claim 1, in which 10 the said projecting means consists of a spring, and said projection delaying means includes a spring-driven rotor adapted to start rotation after departure of the projectile from its starting place, and a safety device which normally prevents the precursor from being projected, said safety device being controlled by said rotor to permit projection of the precursor only after the initial rotor movement.

3. A projectile as claimed in claim 1, in which 20 the said projection delaying means includes a spring-driven rotor adapted to start rotation after departure of the projectile from its starting place, and a safety device which normally prevents the precursor from being projected, said safety device being controlled by said rotor to permit projection of the precursor only after the rotor has rotated through an angle corresponding to the desired time interval between the start of the rotor and the projection of the precursor, 25 said rotor being concentrically arranged around the said precursor.

4. A projectile as claimed in claim 1, in which 30 the said projection delaying means includes a spring-driven rotor adapted to start rotation after departure of the projectile from its starting place, and a safety device which normally prevents the precursor from being projected, said safety device being controlled by said rotor to permit projection of the precursor only after the rotor has rotated through an angle corresponding to the desired time interval between the start of the rotor and the projection of the precursor, said 35 rotor carrying the said fuse cap and fuse in a predetermined eccentric position whereby said fuse cap is brought into alignment with said firing pin after the rotor has turned through a certain angle from its initial position.
